ELECTRIC SHAVER

John Bruecker, Chicago, Ill.

Application August 29, 1936, Serial No. 98,541

38 Claims. (Cl. 30—43)

The present invention relates generally to shavers, that is, apparatus for use in removing beards or face hair as well as effecting depilation of hair on the arms, legs, and other portions of the human body. More particularly the invention relates to that type of shaver which is of the electrical variety and comprises an elongated housing, a cutting head and coacting cutter at one end of the housing, and an electric motor in the housing for driving or actuating the cutter.

One object of the invention is to provide a shaver of this type which is generally an improvement upon and is more efficient in operation than previously designed shavers of the same general character.

Another object of the invention is to provide an electric shaver embodying new principles of construction and operation which make for quicker and closer shaving without irritation of the skin.

Another object of the invention is to provide a shaver of the type under consideration in which the cutting head is U-shaped and embodies a semi-cylindrical skin engaging central part with a plurality of laterally spaced, longitudinally extending series or rows of hair receiving openings therein and the cutter is disposed in and extends longitudinally of said central part of the head and is oscillated back and forth so that it operates to cut the hairs protruding inwardly through the openings.

Another object of the invention is to provide a shaver of the last mentioned type and character in which the cutting head is formed of a rectangular strip of spring metal and the slots therein are formed in such manner that they have dished or flared entrances and are defined by sharp cutting edges which are flush with the inner face of the semi-cylindrical central part of the head and as a result permit of an extremely close shave.

A further object of the invention is to provide a shaver of the aforementioned character which embodies novel means for releasably retaining the cutting head in its operative or connected position.

A still further object of the invention is to provide a shaver in which the cutter is oscillated in a novel manner for hair cutting purposes and is movable radially with respect to the semi-cylindrical central part of the head so that during oscillation thereof and in response to centrifugal action it moves outwards into firm contact with the inner periphery of the central part of

the head and effects an extremely efficient cutting of the hairs protruding in the openings.

Another object of the invention is to provide a shaver having a perforated cutting head of extremely thin flexible material supported independently of the cutter and means whereby the cutter is moved rapidly across the perforated portion of the cutting head and is bodily urged against the same in such manner as to obtain greater efficiency in the shaving operation.

Another object of the invention is to provide an electric shaver embodying such new principles of construction and operation as to enable economical manufacture with improved efficiency and improved convenience in the use of shavers of this class.

Another object of the invention is to provide an improved electric shaver having a perforated cutting head of extremely thin flexible material which may be replaced at a low cost and which is mounted in a novel manner to promote greater ease, safety and comfort in shaving and also to permit of quick and easy replacement.

Other objects of the invention and the various advantages and characteristics of the present electric shaver will be apparent from a consideration of the following detailed description.

The invention consists in the several novel features which are hereinafter set forth and are more particularly defined by claims at the conclusion hereof.

In the drawings which accompany and form a part of this specification or disclosure and in which like numerals of reference denote corresponding parts throughout the several views:

Figure 1 is a perspective of an electric shaver embodying the invention;

Figure 2 is a longitudinal section;

Figure 3 is a section on the line 3—3 of Figure 2;

Figure 4 is a transverse section on the line 4—4 of Figure 2;

Figure 5 is a perspective of one of the end walls and the sides of the locking bracket for the cutting head;

Figure 5A is a perspective of the other end wall of said bracket;

Figure 6 is an enlarged longitudinal section of the head part of the housing;

Figure 7 is a sectional view taken on the line 7—7 of Figure 6 showing in detail the manner in which the cutting head is mounted within the semi-cylindrical central part of the strip formed cutting head;

Figure 8 is a transverse section taken on the 55

line 8-8 of Figure 6 showing in its operative position the key for releasing the cutting head from the locking bracket;

Figure 8A is a perspective of said key;

5 Figure 9 is a diagrammatic view of the electric motor for actuating or driving the shaver;

Figure 10 is an enlarged transverse sectional view of the cutting head and cutter;

10 Figure 10A is a detail sectional view showing the manner in which the head coacts with the slot defining cutting edges on the central part of the head to effect shearing of the hair protruding inwardly through the slots;

15 Figure 11 is a plan view of the thin rectangular spring metal strip which forms the cutting head;

Figure 12 is an enlarged plan or face view of the central part of the cutting head; and

20 Figures 13 and 14 are detail sectional views showing the manner in which the slots are formed in the central part of the head.

The shaver which is shown in the drawings illustrates a preferred form or embodiment of the invention and is designed for use in shaving beards or face hair as well as effecting depilation 25 of hair on the arms, legs, and other portions of the human body. It is of the electrical variety and comprises as the main or essential parts thereof an elongated housing 15, a removable cutting head 16, a blade-type cutter 17, and an 30 electric motor 18. The cutter 17 is adapted, as hereinafter described, and during drive of the electric motor 18, to swing back and forth with respect to the central portion of the cutting head and operates in response to this oscillatory movement and in conjunction with the cutting head to effect the desired shaving or hair depilation.

The housing 15 serves as an enclosure and supporting medium for the various operating parts of the shaver and comprises a head part 19 40 and a handle part 20. The head part serves as the supporting and housing medium for the cutting head 16 and the blade-type cutter 17 and comprises a pair of side walls 21 and a pair of end walls 22 and 23. The end walls are arranged in spaced apart and parallel relation and are substantially wedge-shaped. The large or inner ends of the end walls fit within and are secured to the handle part 20 of the housing, as herein-after described, and the small or outer ends of 50 the end walls are substantially semicircular, as shown in Figure 1 of the drawings. The side walls 21 of the head part 19 of the housing extend between the end walls and are preferably formed integrally with and extend at right angles 55 to the side margins of the end wall 22. The outer ends of the side walls terminate inwardly of the semicircular small ends of the end walls and the inner ends of the side walls 21 are arranged in parallel relation and fit within the handle part 60 20 of the shaver housing. The end wall 22 and the side walls 21 are preferably formed of a one-piece casting and together with the end wall 23 form a compartment 24. The end wall 23 forms a removable closure or cover for the compartment and is removably secured with the edges thereof in abutting relation with the contiguous side edges of the side walls 21 by means of a pair of posts 25 and screws 26, and a pair of posts 27 and screws 28. The posts 25 extend longitudinally across the central portion of the compartment 24 in close proximity to the side walls 21, as shown in Figure 6, and are fixedly secured to the end wall 22 by means of screws 29. The latter extend through holes in said end wall 22 and fit within internally threaded sockets in the

contiguous ends of the posts 25. The screws 26 extend through holes in the end wall 23 and fit within internally threaded sockets in the other or opposite ends of the posts 25. The posts 27 are positioned inwardly of and in parallel relation 5 with respect to the posts 25 and are fixedly secured to the end wall 22 of the head part of the shaver housing by screws 30 which extend through said end wall and fit within internally threaded sockets in the contiguous ends of the posts 27. The screws 30 fit within internally threaded sockets in the other ends of the posts 27 and extend through holes in the end wall 23. When access is desired to the compartment 24 it is only necessary to remove the screws 26 and 10 28. This releases the cover forming end wall 23 so that it may be removed from its operative position wherein the side edges thereof abut against the contiguous side edges of the side walls 21. The handle part 20 of the shaver housing 15 is adapted to be held in the hand. It serves as an enclosure and supporting medium for the electric motor 18 and consists of a pair of complementary end sections 31 and 32. The end section 31 comprises an end wall 33 and an inwardly 15 extending marginal flange 34. The flange, as shown in Figure 3, is U-shaped in conformation and is formed integrally with the end wall 33. The end wall 22 of the head part 19 of the shaver housing fits against and is suitably secured to the inner face of the end wall 33 of the end section 31. The end section 32 of the handle part of the shaver housing is positioned directly opposite the section 31. It forms with the latter a compartment 35 for the electric motor 18 and 20 consists of an end wall 36 and an inwardly extending marginal flange 37. The flange 37 is U-shaped. It conforms to and fits against the flange 34 of the section 31 and together with the latter forms the side wall of the handle part 20. The inner or large end of the end wall 23 of the head part of the shaver housing fits against the inner face of the end wall 36 (see Figure 3). The two end sections of the handle part 20 are secured together by means of a pair of screws 38 which 25 extend through holes in the end wall 36 of the end section 32 and fit within internally threaded sockets in pairs of aligned lugs 39 on the flanges 34 and 37. The end portions of the flanges are 30 knurled or ribbed as shown in Figure 1, so that 35 the handle part of the housing may be held in 40 the hand without likelihood of slippage.

The cutting head 16 is preferably formed of a thin rectangular strip of metal such as spring 45 steel and consists of a semi-cylindrical skin engaging central part 40 and a pair of inwardly extending substantially parallel end parts 41. It extends between the semicircular outer ends of the end walls 22 and 23 of the head part of the shaver housing and is formed by bending the 55 metallic strip so that it is U-shaped in conformation. A locking bracket 42 serves to hold the cutting head in its operative position. This bracket (see Figures 5 and 5A) is located in the compartment 24 and consists of an end wall 43, a pair of sides 44, and an end wall 45. The end wall 43 fits against the inner face of the outer end of the end wall 22 and is fixedly secured in place by means of rivets 46. The outer end of the end wall 43 is semicircular and is concentrically positioned with respect to the semicircular outer end of the end wall 22. It is slightly smaller in diameter than said outer end of the end wall 22 and forms a semicircular shoulder 47 against which one end margin of the semi- 60 70 75 75

cylindrical central part 40 of the cutting head 16 is adapted to abut. The sides 44 of the locking bracket 42 are formed integrally with and extend at right angles to the side margins of the 5 end wall 43 of the bracket and are arranged in parallel relation. They are adapted to have the end parts 41 of the cutting head fit thereagainst, as shown in Figure 6, and serve to hold said end parts of the cutting head in parallel relation. 10 The outer ends of the sides 44 of the locking bracket 42 terminate adjacent to and are spaced inwardly a short distance from the outer end edges of the side walls 21 of the head part 19 of the shaver housing. The end wall 45 of the bracket 42 is formed separately from the sides 44 and is fixedly secured to the cover forming end wall 23 by rivets 48. The outer portion of the end wall is semicircular and is arranged concentrically with respect to the semicircular outer or 15 small end of said wall 23. It is slightly smaller in diameter than the semicircular outer end wall 23 and forms a semicircular shoulder 49 against which the contiguous end margin of the central part 40 of the cutting head is adapted to abut. 20 In assembling the cutting head 16 with respect to the locking bracket 42 the end parts of the head are first brought into parallel relation and are then inserted between the outer end edges of the sides 44 of the locking bracket and the 25 sides 21 of the head part 19 of the shaver housing and moved inwardly into lapped relation with respect to said sides 44 of the locking bracket. When the cutting head is in place the end edges of the semi-cylindrical central part 40 fit against and are supported by the semicircular shoulders 47 and 49. The semicircular margins of the outer ends of the end walls 22 and 23 of the head part of the shaver housing, that is the portion of said margins which project beyond 30 the shoulders 47 and 49 serve as abutments whereby endwise movement of the cutting head is prevented. The shoulders 47 and 49 are truly semicircular and hence serve not only as abutments for the central part 40 of the cutting head 35 but also to hold said part in such manner that its conformation is truly semi-cylindrical. Studs 50 on the outer ends of the side walls 21 of the head part of the shaver housing serve to guide the end parts 41 of the cutting head 16 against the 40 sides 44 of the locking bracket 42 during assembly of the cutting head with respect to the locking bracket and serve additionally to hold said end parts 41 in lapped or abutting relation with respect to the sides 44. These studs fit against 45 the inner faces of the side walls 21 and are secured in place by means of rivets 51. The cutting head 16 is releasably held in assembled or fixed relation with the locking bracket 42 by means of a pair of springs 52. These springs are 50 of the coil or convolute type and are mounted on the posts 25 which extend across the compartment 24 and support the screws 26 whereby the cover forming end wall 23 of the head part 19 of the shaver housing is releasably held in place. 55 The ends of the springs which are disposed adjacent to the end wall 22 of the head part 21, extend radially with respect to the post 25 and abut against the side walls 21 so that they prevent the springs from unwinding. The other 60 ends of the springs extend outwardly and then inwardly as shown in Figure 6, and form fingers 53 which extend through apertures 54 in the end parts 41 of the cutting head and also through apertures 55 in the sides 44 of the locking bracket 42. The springs 52 are wound or coiled 65 in such manner that the fingers 53 tend to swing toward one another. As a result of this arrangement the fingers when they extend through the apertures 54 urge the cutting head inwardly and serve to hold the semi-cylindrical central part 5 70 of the head in abutting relation with the semicircular shoulders 47 and 49. The apertures 55 in the sides 44 of the locking bracket are larger than the apertures 54 so that the fingers 53 are free at all times to hold the cutting head 10 under spring tension. The springs 52 constitute simple means for releasably holding the cutting head in its operative position, that is in a position wherein the end parts 41 lap the sides 44 of the locking bracket 42 and the semi-cylindrical central part 40 abuts against the shoulders 15 47 and 49 on the end walls of the bracket. Release of the cutting head 16 for cleaning or replacement purposes is effected by means of a key 56 (see Figure 8A). This key is U-shaped and 20 embodies a pair of substantially parallel legs 57. The latter have beveled surfaces 58 at the outer ends thereof and are adapted to slide within a pair of centrally split guide tubes 59 which extend across the compartment 24 and consist of 25 sections 59^a and 59^b. The sections 59^a extend through and are suitably secured to the end wall 22 of the head part 19 of the shaver housing and the sections 59^b are aligned with and spaced from sections 59^a, as shown in Figure 8, and extend through and are suitably secured in the cover forming wall 23 of said head part 19. 30 The fingers 53 of the springs 52 extend across the spaces between the sections 59^a and 59^b of the guide tubes 59. When the legs 57 of the key 56 are inserted into and move through the tubes 59 the beveled surfaces 58 encounter the fingers 53 and cam or wedge the latter outwards, as shown by dotted lines in Figure 6 of the drawings. When they are in their cammed or wedged 35 position the fingers 53 are disengaged with respect to the apertured portions of the end parts 41 of the cutting head 16 and the cutting head is hence free so that it may be removed from the locking bracket 42. The legs 57 of the key 56 40 may be inserted into the tubes 59 from the end wall of the shaver housing. When it is desired to assemble the cutting head 16 with respect to the locking bracket 42 the legs 57 of the key 56 are inserted into the guide tubes 59 and then 45 moved inwards until they pass across the space between the sections 59^a and 59^b and operate to cam or wedge outwards the fingers 53 of the springs 52. Thereafter the end parts 41 of the cutting head 16 are inserted between the outer 50 end edges of the sides 44 of the bracket 42 and the side walls 21 of the head part 19 and moved inwards across the outer faces of the sides 44 until the apertures 54 are in registry with the apertures 55 and the semi-cylindrical central 55 part 40 is brought into abutment with the semicircular shoulders 47 and 49. Thereafter the key 56 is removed from the head part 19 of the shaver housing. Immediately upon removal of the legs 57 of the key from the guide tubes 59 60 the fingers 53 of the springs 52 swing inwards into a position wherein they interlock with the apertured portions of the end parts 41 of the locking head and serve to hold the head in place. 65 During assembly of the cutting head with respect to the locking bracket 42 the studs 50, as hereinbefore described, serve to guide the end parts 41 of the head so that they move in contact with, and parallel to, the sides 44 of the locking bracket 42. The semi-cylindrical cen- 70 75

tral part 40 of the cutting head 16 is provided with a plurality of series of hair receiving slots 60. My invention contemplates the use of hair receiving perforations or openings of any shape and arrangement suitable for the purposes herein disclosed. In the embodiment of my invention shown in the drawings and herein described I employ a series of slots which extend from one end edge of the central part 40 to the other and are arranged at an angle of approximately 10° with respect to the end edges. As shown in Figures 11 and 12, the slots of one series are staggered with respect to the slots of the contiguous series. The slots are formed by placing the cutting head forming strip between a pair of dies one of which embodies a plurality of ribs corresponding in number and design to the slots and the other of which embodies a plurality of recesses for receiving the ribs of what may be termed the male die. When the dies are brought together with the cutting head forming strip therebetween the ribs of the male die deflect the metal of the strip so that the latter has indentations on one side thereof and projections on the other side. The ribs on the male die are greater in height than the strip is thick with the result that the indentations in the one side of the strip that is the skin engaging face, are of greater depth than the strip. After the strip has been subjected to the action of the dies, the projections on the inner face of the strip are ground off with the result that the slots 60 are formed. Because of the specific manner in which the slots are formed the cutting head has on the outer face thereof a plurality of series of cavities 61 and embodies on its inner face cutting edges 62. The latter define the slots and are flush with the inner face of the cutting head. When the cutting head is moved over the skin for shaving or hair depilation purposes the skin works its way into the cavities 61 and the hairs when they encounter the slots, snap or work their way through the slots. Because of the cavities and the manner in which they operate to receive the skin, the cutting edges 62 are aligned with the hairs at the points at which they protrude from the skin. As a result of this, the blade type cutter 17 when it is oscillated within the cutting head 16, as hereinafter described, effects an extremely close cutting of the hairs. The cavities 61 are dished and serve to direct the hair through the slots 60. The slots are the same in length, as shown in Figure 12, and each slot is spaced from the adjoining slots of its series a distance slightly less than the slot's length. As a result of this and because the slots of every other series are staggered with respect to the slots of alternate series all of the hairs encountered by the cutting head during each sweep of the housing in connection with a shaving or hair depilation operation are encountered by the slots 60 and are subjected to the cutting action of the blade type cutter 17. The cutter, as shown in the drawings and as described hereafter, extends at right angles to the end edges of the semi-cylindrical central part 40 of the cutting head. As a result of this and the fact that the series of slots 60 extend at a slight angle with respect to said end edges a thorough shearing or scissors action is had when the cutter 17 traverses the sharp cutting edges which define the slots 60. The slots 60 are slightly wider than a normal hair. The cutting head 16 is preferably .003 of an inch in thickness so that it is readily bendable and a close shave may be had. In using the

shaver cutting of the hair is effected when the cutting head 16 is moved in a direction directly opposite to that in which the hairs normally project. When the cutting head is moved in such direction the hairs as a result of the action of the cavities 61 readily work their way into and through the slots 60. By forming the cutting head 16 of a thin strip of spring metal as contradistinguished from a casting or a screw machine part the cost of production is extremely low and it is possible to replace a damaged or worn out head with a new one at an extremely small cost. In order to permit of ready discharge of cut hairs from the compartment 24, holes 63 are formed in the cutting head and holes 64 are formed in the side and end walls of the head part 19 of the shaver housing 15. The holes 63, as shown in Figure 11, are formed in the semi-cylindrical central part 40 of the cutting head at the points where such part joins the end parts 41, and is, directly adjacent to the outermost series of slots 60.

The cutter 17 extends between the end walls 43 and 45 of the locking bracket 42 and is preferably in the form of a metallic stamping. It is rectangular, as shown in Figure 7 of the drawings and extends radially from and is carried by a rock-bar 65. This bar extends between said end walls 43 and 45 and is pivotally supported by a pair of pintles 66 so that it is free to rock about its longitudinal center. The pintles 66 extend through and are centered with respect to the rounded outer ends of the end walls 22 and 23 of the head part 19 of the shaver housing and also extend through and are centered with respect to the end walls 43 and 45 of the locking bracket 42. The inner ends of the pintles project inwardly with respect to said side walls 43 and 45 and are journaled in bearings 67 in sockets 68 in the ends of the rock bar 65. The bearings 67 are preferably of the oil treated wooden variety in order to dispense with lubrication. The cutter 17 embodies a pair of laterally spaced, inwardly extending tongues 69. These tongues (see Figure 7) fit within and extend transversely through a pair of sockets 70 in the central portion of the rock-bar and serve to connect the cutter to the bar so that it oscillates or rocks back and forth with the bar and at the same time is free to slide radially relatively to the bar and into contact with the inner face or periphery of the semi-cylindrical central part 40 of the cutting head 16. The sockets 70 extend transversely through the rock-bar 65, as shown in Figure 10, and have restricted or narrow mouth portions which are slightly greater in thickness than the tongues 69. The mouth portions of the sockets are defined by means of pairs of oppositely facing ribs 71 which are formed as integral parts of the bar and have curved opposed surfaces 72 for engaging the root parts of the tongues. The curved surfaces 72 of the ribs 71 together with the tongues 69 constitute sliding connections whereby the cutter 17 is supported for radial movement with respect to the rock-bar 65. By reason of the fact that the sockets 70 are greater in width than the tongues 69 and have restricted mouth portions, they are free to rock or pivot to a limited extent relatively to the rock-bar. A compression spring 73 and a plunger 74 serve to urge the cutter 17 outwards into contact with the inner face of the semi-cylindrical central part 40 of the cutting head 16. The spring 73 is disposed in a bore 75 in the central portion of the rock-bar 65. The plunger 74 comprises a head 76 and a stem 77. The head is

slidably mounted in the outer end of the bore 75 and is held against ejection by an annular ring-shaped lip 78 at the outer end of the bore. The stem 77 extends through the lip and engages the inner side edge of the cutter. The rock-bar 65 is rocked for cutter oscillating purposes by means of a rotary disk 79 and an eccentric pin 80 on the disk. The disk, as hereinafter described, is driven at a comparatively high speed by the electric motor 18. It is disposed in the compartment 24 between the sides 44 of the locking bracket 42. The pin 80 is suitably connected to the outer end face of the disk 79 so that it is eccentrically disposed with respect to the disk's axis and embodies a ball 81 at its outer end. This ball, as shown in Figures 6, 7 and 10 of the drawings, fits between a pair of plates 82 which are connected to and extend inwardly from the sides of the rock bar 65. Preferably the plates 82 are formed of fiber or like material and are secured in place by pins 83 which extend transversely through the central portion of the rock bar. During drive or rotation of the disk 79 by the electric motor 18 the pin 80 due to its eccentric position or location with respect to the disk travels in a circular course and operates through the medium of the ball 81 and the plates 82 to rock the bar 65. During rocking of the bar the cutter 17 sweeps or oscillates back and forth around the inner face 30 of the cutting head 16 and in conjunction with the cutting edges 62 effects close cutting of all hairs which project through the slots 60. The spring pressed plunger 74 in conjunction with centrifugal force serves to hold the outer side 35 face of the cutter in firm contact with the inner face of the central part 40 of the cutting head and hence an efficient cutting action is always obtained. As the result of the action of the spring pressed plunger and centrifugal force the cutter is automatically moved outwards when the cutting surface thereof becomes worn and wear is thus automatically compensated for. The pin 80 is preferably located with respect to the center of the disk 79 so that it operates to rock the bar 40 45 through an arc of 90°. When the cutter 17 is swung in one direction the leading edge of the cutting surface, that is, the outer side surface of the cutter operates in conjunction with the cutting edges 62 to cut all of the hair which projects through the slots 60 and when the cutter 17 is swung in the other direction the opposite edge of the cutting surface coacts with the cutting edges 62 to effect the desired cutting action 50 as far as the hairs are concerned. This is attributable to the fact that the tongues 69 and the sockets 70 permit the cutter 17 to rock to a slight extent relatively to the rock bar 65 and as a result the cutter when it is swung clock-wise is located to the left of the axes of the sockets 70 and when 55 60 65 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840 845 850 855 860 865 870 875 880 885 890 895 900 905 910 915 920 925 930 935 940 945 950

movement of the cutter increases relatively to the bar the angle at which the cutter traverses the cutting edges 62 increases and hence there is always a new or sharp cutting edge in contact with the inner face or periphery of the semi-cylindrical central part 40 of the cutting head. Due to the fact that the cutter is slidably with respect to the rock bar and is free to rock or swing laterally to a limited extent relatively to the bar, the cutter not only in response to centrifugal force engages at all times the inner periphery of the central part 40 of the head but also sharpens itself automatically. When it is desired to remove the cutter for repair or replacement purposes it is only necessary to remove the cutting head 17 by releasing the fingers 53 of the springs 52 by means of the key 56, as hereinbefore described. The electric motor 18 is of the so-called induction impulse type. It is disposed within the compartment 35 in the handle part 20 of the shaver housing 15 and consists of an armature 84 and a pair of field magnets 85 and 86. The armature 84 consists of a series of metal plates or laminations 84a, and is mounted on an armature shaft 25 30 35 40 45 50 55 60 65 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840 845 850 855 860 865 870 875 880 885 890 895 900 905 910 915 920 925 930 935 940 945 950

a plate 110 which is formed of insulating material and is secured by a screw 111 to a bracket 112 on a plate 113. This plate is formed of insulating material and is secured in any suitable manner to the inner or large end of the end wall 22 of the head part 19 of the shaver housing. The movable contact 107 is mounted on one end of a spring strip 114 so that it is movable to and from the fixed contact 106. The other end of the strip is attached to a bracket 115 which is secured to the plate 113 of insulating material. The cam 108 is in the form of a flat plate and is fixedly secured to the collar 95 on the armature shaft 87. It is formed of insulating material and is arranged so that during rotation of the armature shaft the side edges thereof successively contact with the spring strip 114 and move the contact 107 into engagement with the contact 106. The spring strip is supported by the bracket 115 so that the contact 107 is normally out of engagement with the contact 106. When the cam 108 is turned to a position wherein it brings the contact 107 into engagement with the contact 106 the circuit through the field magnets 85 and 86 of the motor is completed and the armature in response to the action of the magnets is caused to rotate. Continued rotation of the armature results from the current impulses which are governed by or results from the action of the circuit interrupter 105. An adjusting screw 116 is carried by a plate 117 on the bracket 115 and engages the spring strip 114 between the cam 108 and said bracket 115. By adjusting the screw 106 to or from the spring strip 114 the duration of engagement of the contacts 106 and 107 during each half revolution of the cam 108 may be controlled and it is thus possible to set the interrupter so the current impulses are such that maximum power is obtained during drive of the motor.

When the cam 108 of the circuit interrupter 105 is out of engagement with the spring strip 115 and it is desired to start the shaver it is only necessary to turn quickly the shaver housing 15 about the axis of the armature shaft 87. As a result of the inertia of the armature shaft this turning movement of the housing results in the spring strip 114 being brought into engagement with one side edge of the cam 108. Upon engagement of the spring strip with such side edge of the cam the contact 107 is brought into engagement with the contact 106 and the circuit through the field magnets 85 and 86 is thus closed. Upon closing of this circuit the motor starts, as previously described. During drive or operation of the motor the ball 81 in response to the action of the eccentric pin 80 rocks the rock bar 65 back and forth and oscillates the blade-type cutter 17. When the semi-cylindrical central part 40 of the cutting head 16 is moved over the skin in a direction opposite that in which the hairs on the skin extend the hairs work their way through the slot 60 and are trimmed or cut in response to the shearing action of the cutter 17 and the cutting edges 62.

The herein described electric shaver is extremely efficient in operation and due to the small number of parts and the specific construction and character of the cutting head and cutter may be manufactured at a low and reasonable cost. Due to the specific formation of the slots 60 and the action of the skin receiving cavities 61 an extremely close shave may be obtained with the shaver. Because the central part 40 of the cutting head 16 is semi-cylindrical and embodies rows

of hair receiving slots substantially throughout, an effective shave or hair depilation is effected regardless of the angle at which the skin engaging part of the cutting head is placed against the skin.

The invention is not to be understood as restricted to the details set forth, since these may be modified within the scope of the appended claims, without departing from the spirit and scope of the invention.

Having thus described the invention, what I claim as new and desire to secure by Letters Patent is:

1. In a shaver, the combination of a skin-engaging cutting head of thin spring metal having hair-receiving openings therein, a cutter, means independently supporting in a curved plane the opposite margins at the longitudinal edges of the cutting head with the openings disposed in the curved portion of the head intermediate said opposite margins and maintained in operative position independently of the cutter, the cutter being bodily forced outwardly against and movable across the inner face of the curved portions 25 of the cutting head between its oppositely supported margins.

2. In a shaver, the combination of a skin-engaging cutting head of thin spring metal, a cutter, fixed arcuate shoulders at the longitudinal edges 30 of the cutting head, means holding the cutting head with its marginal edges seated against said arcuate shoulders, the arcuate portion of the cutting head between said shoulders being perforated to provide hair-receiving openings, said shoulders and holding means serving to maintain the perforated portion of the cutting head in its operative arcuate plane independently of the cutter, and means for moving the cutter across the inner face of the curved portion of the cutting 40 head between the shoulders and for causing the cutter to be forced outwardly so that its cutting edge bears with pressure against said curved portion when so moved.

3. In a shaver, the combination of a skin-engaging cutting head consisting of a strip of thin resilient material having a portion flexed in a curved plane provided with hair-receiving openings, a flat cutter, means for oscillating the cutter so that its cutting edge moves back and forth across the inner face of the curved portion of the cutting head, and means for causing the cutter to be bodily moved outwardly against the inner side of said curved portion when oscillated.

4. A shaver having a cutting head to rest 55 against the skin, of extremely thin spring metal having hair-receiving openings at its medial portion, each opening having a cutting edge at the side opposite from the skin engaging side, the cutting edge being flexed at its medial portion to 60 arcuate form, fixed arcuate shoulders at the longitudinal edges of the cutting head for supporting the opposite arcuate marginal edges of said medial portion, means engaging each end of the cutting head for holding it firmly against said shoulders comprising engaging elements operable to draw the cutting head into said holding position and also operable for releasing its ends, and a cutter having a shearing action against the cutting edges of the cutting head intermediate the 70 supported marginal edges when said cutter is moved across the cutting edges of said cutting head.

5. In a shaver, a cutting head to rest against the skin comprising a flat strip of thin spring 75

- 5 steel having hair-receiving openings closely spaced substantially throughout a cutting portion, each opening having a cutting edge at one side of the cutting head, a cutter, means independent of the cutter for holding the cutting portion of the head flexed in substantially semi-cylindrical form with its longitudinal marginal ends definitely supported in said semi-cylindrical form, means for moving the cutter in a shearing action about 10 an axis concentric with said semi-cylindrical form, and means whereby the cutter is bodily moved outwardly against the cutting edges on the inner side of the cutting head when moved in said shearing action.
- 15 6. A shaver having a skin-engaging part of sheet spring steel of approximately .003 of an inch thickness flexed to arcuate form and fixedly supported at its arcuate ends in said form, said arcuate part having hair-receiving openings closely spaced substantially throughout its arcuate portion, and a cutter extending longitudinally of and within said arcuate portion and mounted to move about an axis concentric with said arcuate ends and having a cutting edge movable across 20 the inner face of said openings by movement of the cutter about its said axis, and means whereby the cutter is bodily moved outwardly against said inner face when moved across the same in a cutting action.
- 25 7. A shaver having a flat cutter blade, means for oscillating said blade at a high speed and said blade being free to move outwardly under centrifugal force, and an extremely thin skin engaging cutting head having a closely perforated portion flexed to arcuate form arranged so that the oscillating blade bears against the inner side of the perforated portion and in intimate cutting relation with the inner edges of the perforations.
- 30 8. In a shaver, the combination of a skin-engaging cutting head of thin spring metal having hair-receiving openings, means for retaining and supporting the medial portion of the head fixed in arcuate form, a cutter, means whereby said cutter is movable across the inner face of the arcuate portion of the head and free for outward radial movement by centrifugal force into intimate contact with the inner face of the head.
- 35 9. A shaver having a cutting head to rest against the skin, of thin metal flexed to arcuate form and having hair-receiving openings in its arcuate portion, a cutter, means independent of the cutter supporting opposite arcuate marginal edges of the arcuate portion of the cutting head against inward deflection with the intermediate arcuate portion free to flex, the cutter extending lengthwise between said edges and supported for free movement outwardly against the cutting head, and means for operating the cutter in a cutting action against the inner face of the cutting head in which action the cutter has constant outward pressure against the flexible portion of the cutting head.
- 40 10. A shaver comprising the combination of a skin-engaging cutting head of thin spring metal having hair-receiving openings, means for fixedly supporting the margins at the longitudinal edges of the medial portion of the head and retaining it in arcuate form, a cutter support, means for oscillating the support, and a cutter carried by the support to engage the arcuate inner face of the cutting head and radially movable outwardly against the flexible portion of the head by centrifugal force.
- 45 11. A shaver having a cutting head to rest against the skin, of extremely thin material provided with hair-receiving openings and flexed to arcuate form, means supporting the opposite marginal arcuate edges of the blade against 5 deflection from said arcuate form, a cutter extending lengthwise between said opposite arcuate edges supported for free movement outwardly against the inner face of the cutting head, means for oscillating the cutter at a high speed 10 so that during oscillation and in response to centrifugal action it moves outwardly into intimate shearing contact with the cutting head, and means yieldingly urging the cutter outwardly against the cutting head in conjunction with said 15 centrifugal action.
- 50 12. A shaver having a cutting head to rest against the skin, of spring metal of approximately .003 of an inch thickness flexed to an arcuate form and closely perforated throughout a portion of said arcuate form to provide hair-receiving openings and having cutting edges at inner edges of said openings, a cutter extending longitudinally of the head and mounted for oscillation with its longitudinal edge moving back 20 and forth across the inner face of the perforated portion, the cutter being free to move outwardly against the head, and means for oscillating the cutter at a high rate of speed whereby it is urged by centrifugal force against the head and 25 has intimate shearing action throughout its length with the cutting edges at the inner edge of the perforations.
- 55 13. In a shaver, comprising the combination of a skin-engaging cutting head of thin spring metal having hair-receiving openings, means for fixedly supporting the margins of the medial portion of the head and retaining it in arcuate form, a pivotally movable cutter-support, a cutter blade carried by said support and having its 40 outer edge movable across and engageable with the inner face of the arcuate portion of the head, and means for oscillating the support to actuate the blade and cutter, the blade being circumferentially tiltable in the support in opposite directions responsively to the reversal of movement 45 of the support.
- 60 14. In a shaver, comprising the combination of a skin-engaging cutting head of thin spring metal having hair-receiving openings, means for fixedly supporting the margins of the medial portion of the head and retaining it in arcuate form, a pivotally movable cutter-support, a cutter-blade carried by said support and having its 50 outer edge movable across and engageable with the inner face of the arcuate portion of the head, and means for oscillating the support to actuate the blade and cutter, the blade being circumferentially tiltable in the support in opposite directions on an axis between the axis of the support and the inner face of the blade responsively to the reversal of movement of the support.
- 65 15. In a shaver, comprising the combination of a skin-engaging cutting head of thin spring metal having hair-receiving openings, means for fixedly supporting the margins of the medial portion of the head and retaining it in arcuate form, a pivotally movable cutter-support, a cutter-blade carried by and radially slidable in said support and having its outer edges movable across and engageable with the inner face of the arcuate portion of the head, and means for oscillating the support to actuate the blade and cutter, the blade being circumferentially tiltable 70
- 75

in the support in opposite directions responsive to the reversal of movement of the support.

16. A shaver having a cutting head to rest against the skin, provided with hair-receiving openings each having a cutting edge opposite from the skin-engaging side, a cutter-blade having opposed cutting edges, and an oscillating holder for moving the cutter-blade back and forth in cutting strokes in which the leading edge of the cutter-blade is in shearing relation with the cutting edges of the head and the trailing edge is held away from said cutting edges, the cutter-blade having a tilting movement at the end of each cutting stroke upon and with respect to the holder whereby to shift the leading cutting edge out of said shearing relation with the cutting edges of the head and move the trailing cutting edge into said relation.

17. In a shaver, a cutting-head of approximately semi-cylindrical form having hair-receiving openings, a flat cutter-blade having opposed cutting edges at one end, a blade-holder mounted to oscillate about an axis concentric with the semicylindrical cutting head for moving the cutter-blade back and forth in shearing relation with the cutting head, and means whereby the cutter-blade has a limited pivotal movement upon and with respect to the holder about an axis eccentric with respect to the pivot axis of the holder.

18. In a shaver, a cutting head of approximately semicylindrical form having hair-receiving openings, a flat cutter-blade having opposed cutting edges at one end, a blade-holder mounted to oscillate about an axis concentric with the semicylindrical cutting head for moving the cutter-blade back and forth in shearing relation with the cutting head, means whereby the cutter-blade has a limited pivotal movement upon and with respect to the holder about an axis eccentric with respect to the pivot axis of the holder, and means for oscillating the holder comprising an eccentric pin rotating about an axis perpendicular to the pivot axis of the blade-holder.

19. In a shaver, a cutting head of approximately semicylindrical form having hair-receiving openings, a flat cutter-blade having opposed cutting edges at one end, a blade-holder mounted to oscillate about an axis concentric with the semicylindrical cutting head for moving the cutter-blade back and forth in shearing relation with the cutting head, means whereby the cutter-blade has a limited pivotal movement upon and with respect to the holder about an axis eccentric with respect to the pivot axis of the holder, means for oscillating the holder comprising an eccentric pin rotating about an axis perpendicular to the pivot axis of the blade-holder, a ball end on the pivot pin, and opposed parallel members on the holder between which the ball end operates to oscillate the holder.

20. In a shaver, the combination of a cutting head of approximately semicylindrical form having hair-receiving openings, a flat cutter-blade having a cutting edge at its outer end, a holder for the blade mounted to oscillate about an axis concentric with the semicylindrical cutting head and provided at its inner end with an elongated groove parallel with said axis, the cutter-blade being free to move outwardly upon and with respect to the holder to urge its cutting edge against the cutting head, and means for oscillating the holder comprising an eccentric pin mounted to rotate about an axis perpendicular

to the axis of the holder provided with a ball extending into and slidable in the groove.

21. As a new article of manufacture, a shaver comprising a housing, a hollow cutting head on the housing, comprising a skin engaging part and embodying in said part a plurality of hair-receiving slots with outwardly flared entrance cavities and sharp slot defining cutting edges flush with the inner face of said part, a cutter disposed within and extending longitudinally of said part and engaging the inner face of the latter, and power means within the housing for moving the cutter back and forth and causing it to coat with said cutting edges in severing the hairs protruding inwardly through the slots. 15

22. As a new article of manufacture, a shaver comprising a housing, a hollow cutting head on the housing comprising a substantially semi-cylindrical skin engaging part and embodying in said part a plurality of laterally spaced longitudinally extending rows of hair receiving slots with outwardly flared entrance cavities and sharp slot defining cutting edges flush with the inner face of said part, a blade-type cutter disposed in and extending substantially radially with respect to said skin engaging part of the cutting head, and power means in the housing for oscillating the cutter so as to cause it to coat with said cutting edges in severing the hairs protruding inwardly through the slots. 20

23. In a shaver, a cutting head to rest against the skin comprising a strip of extremely thin spring metal having closely arranged hair-receiving openings at its medial portion and a single opening adjacent to each end centrally thereof, fixed arcuate shoulders against which the opposite margins of said medial portion at the longitudinal edges of the head are adapted to seat, and means engaging in said single openings for holding the cutting head in working position 30 on said shoulders. 35

24. As a new article of manufacture, a shaver comprising a housing, a hollow cutting head mounted on the housing and having substantially semi-cylindrical skin engaging parts with a plurality of hair receiving slots extending therethrough, a rock-bar centrally positioned within and extending lengthwise of said skin engaging part of the head, a blade-type cutter projecting substantially radially from the bar so that the 50 outer edge thereof contacts with the inner face of said skin engaging part of the head, tongue and socket connections between the inner portion of the blade and the rock-bar whereby the cutter is connected for rocking movement with the ball 55 and at the same time is free to rock to a small degree relatively to the bar and also to move outwards in response to centrifugal force towards said skin engaging part of the head, and power driven means disposed in the housing for rocking 60 the bar and thus causing the cutter in response to oscillation thereof to sever the hairs protruding inwardly through the slots. 65

25. In a shaver, a cutting head of extremely thin resilient material having a closely perforated portion flexed to arcuate form, a single flat cutter blade and means for oscillating said blade rapidly across the inner side of said arcuate perforated portion and said blade being bodily urged outwardly against said inner side. 70

26. In a shaver, a flat cutter blade, a strip of extremely thin resilient metal having hair-receiving perforations with cutting edges at one side and held taut with its perforated portion flexible and supported independently of the cutter blade, 75

the cutter blade being pressed outwardly against said cutting edges, and means for moving said blade rapidly across the same in intimate shearing engagement therewith.

5 27. In a shaver, an extremely thin skin-engaging cutting head having a closely perforated portion of arcuate form and cutting edges at the inner end of the perforations, a flat cutter blade, 5 means for oscillating said blade at a high speed 10 with its narrow cutting edge in line contact with the cutting edges throughout the length of said perforated portion, the blade being free to move outwardly against said cutting edges, and means 15 for causing the blade to press outwardly against said cutting edges.

28. In a shaver, an extremely thin skin-engaging cutting head having a closely perforated portion of arcuate form and cutting edges at the inner end of the perforations, a flat cutter blade, 20 means for oscillating said blade at a high speed with its narrow cutting edge in line contact with the cutting edges throughout the length of said perforated portion, the blade being free to move outwardly against said cutting edges and arranged so that it has bodily movement under centrifugal force urging it into engagement with 25 said cutting edges.

29. In a shaver, a flat cutter blade, a cutting head of extremely thin resilient material provided with hair-receiving perforations having cutting edges at one side and supported independently of the cutter blade, means for moving the blade rapidly across said perforated portion in a cutting action, the blade being free to move outwardly against the cutting edges, and means for causing the blade to press outwardly against 30 said cutting edges during the cutting action.

30. In a shaver, a single cutter blade, a strip of extremely thin spring metal having a closely 40 perforated portion, means independent of the blade for supporting said strip with its perforated portion free to flex, means for rapidly moving the blade across the perforated portion in successive cutting movements, and means for causing the blade to move outwardly under pressure 45 against the inner face of the cutting head during said movements.

31. In a shaver, a cutter blade, a cutting head of extremely thin resilient material having a 50 perforated portion flexed to arcuate form and maintained in said arcuate form independently of the blade, and means for rapidly oscillating the blade and causing it to be moved outwardly against the inner side of said arcuate portion.

55 32. In a shaver, a single flat cutter blade, a cutting head of extremely thin resilient material having a perforated portion flexed to arcuate form and maintained in said form independently of the blade, and means for oscillating the blade 60 at a high speed with its narrow edge urged under pressure against the inner side of the arcuate perforated portion.

33. In a shaver, a single flat cutter blade, a cutting head of extremely thin resilient material having a perforated portion flexed to arcuate form and maintained in said form independently of the blade, means for oscillating the blade at a high speed with its narrow edge traversing the inner side of the arcuate perforated portion, and means for causing the blade to be urged bodily outwardly against the arcuate perforated portion while traversing the same so as to have tension along the length of said narrow edge against 65

said perforated portion throughout the travel back and forth across said portion.

34. In a shaver, a cutter blade, a cutting head to bear against the skin comprising a strip of thin spring metal closely perforated throughout a cutting portion, means holding the cutting head with its cutting portion flexed to arcuate form and retained in said arcuate form independently of the blade, means for rapidly oscillating the blade at the inner side of the cutting head so that the cutting edge of the blade traverses the arcuate perforated portion, and means causing the blade to be urged outwardly against the inner side of said arcuate perforated portion while traversing the same. 10 15

35. In a shaver, the combination of a skin-engaging cutting head of thin spring metal having a medial portion provided with hair-receiving openings, a cutter, means independent of the cutter for supporting the longitudinal edges of said medial portion in arcuate form and thereby retaining the medial portion flexed in similar arcuate form, means for moving the cutter in a shearing action across the inner face of the arcuate medial portion, the cutter being free for 20 outward movement to impinge against said inner face, and means whereby the cutter will be yieldingly pressed outwardly against the inner face of the head when operated in said shearing action. 25

36. In a shaver, a body providing a handle part 30 and a head part, a motor in the handle part, the head part constituting a housing having an opening at its end remote from the handle part, a cutter blade mounted within the head part for oscillation about a fixed axis, means driven by 35 the motor for oscillating the cutter blade, a cutting head consisting of a strip of thin resilient material perforated at its medial portion to provide hair-receiving openings, the cutting head being normally in operative position within said 40 opening in the head part with its perforated portion flexed to arcuate form in cooperative relation with the cutter blade and projecting beyond the housing and with its opposite end portions located within the housing, and holding means 45 for retaining the cutting head in said operative position including elements within the housing movable into and out of engagement with said end portions of the cutting head and means operable from the exterior of the body to actuate 50 said elements for releasing them from the cutting head.

37. In a shaver, a cutter blade having a flat body and a cutting edge in a flat plane, a cutting head having a thin perforated portion in a 55 curved plane, the blade having its cutting edge extending longitudinally of the cutting head and being free to move outwardly under centrifugal force against the inner side of the curved portion, and means for rapidly moving the blade across 60 said curved portion.

38. In a shaver, a cutter blade having a flat body and a longitudinal cutting edge in a flat plane, a cutting head having a thin perforated portion in a curved plane, the blade having its cutting edge extending longitudinally of the cutting head and being free to move outwardly against the inner side of the curved portion, means for rapidly moving the blade across said 65 curved portion, and means for causing the blade to be bodily moved outwardly into shearing engagement with the cutting head when so operated. 70

JOHN BRUECKER.
